UNITED STATES PATENT OFFICE.

ROUPEN K. YACOOBIAN, OF PHILADELPHIA, PENNSYLVANIA.

DESIGN FOR A WATER-FAUCET ATTACHMENT FOR MIXING HOT AND COLD WATER.

No. 40,106.

Specification for Design.

Patented June 29, 1909.

Application filed April 2, 1909. Serial No. 487,594. Term of patent 14 years.

To all whom it may concern:

Be it known that I, ROUPEN K. YACOOBIAN, a subject of the Sultan of Turkey, residing at Philadelphia, in the county of Philadelphia and State of Pennsylvania, have invented a new, original and ornamental Design for a Water-Faucet Attachment for Mixing Hot and Cold Water, of which the following is a specification, reference being had to the accompanying drawing, forming part thereof.

Figure 1, is a perspective view of a water

faucet attachment showing my new design. Fig. 2, is a view in front elevation thereof, and Fig. 3, is an end view thereof.

I claim:

The ornamental design for a water faucet attachment for mixing hot and cold water, as shown.

ROUPEN K. YACOOBIAN.
